[57] CLAIM

The ornamental design for a vacuum chuck for a lathe for making optically-smooth surfaces, as shown and described.

DESCRIPTION

FIG. 1 is a top, front and right side perspective view of a vacuum chuck for a lathe for making optically-smooth surfaces showing our new design;

FIG. 2 is a top plan view;

FIG. 3 is a front elevational view;

FIG. 4 is a right side elevational view;

FIG. 5 is a left side elevational view;

FIG. 6 is a rear elevational view; and,

FIG. 7 is a bottom plan view thereof.

FIG. 2.

FIG. 5.

FIG. 3.

FIG. 4.

FIG. 7.

FIG. 1.

FIG. 6.
